UNITED STATES PATENT OFFICE

CLARENCE A. ROMINE, OF PLYMOUTH, INDIANA

STONE BOX FOR SUCTION PUMPS

Application filed September 26, 1930. Serial No. 484,652.

The present invention relates to a stone box to be used in connection with a sand suction pump and has for its prime object to provide means for separating large stones from the sand to prevent the entrance of said stones into the sand suction pump and means whereby the stones may be expeditiously dumped from the box when desired.

A still further very important object of the invention resides in the provision of a dump stone box of this nature which is exceedingly simple in its construction, comparatively inexpensive to manufacture, easy to manipulate, compact and convenient in its arrangement of parts, fairly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of an apparatus embodying the features of my invention,

Figure 2 is an end elevation thereof,

Figure 3 is a side elevation thereof,

Figure 4 is a vertical longitudinal section therethrough taken substantially on the line 4-4 of Figure 1,

Figure 5 is a fragmentary horizontal section taken substantially on the line 5-5 of Figure 4,

Figure 6 is a detail section taken substantially on the line 6-6 of Figure 5,

Figure 7 is a detail section taken substantially on the line 7-7 of Figure 1,

Figure 8 is a fragmentary detail view of one end of the grate.

Referring to the drawings in detail it will be seen that the box comprises a front wall 5, a rear wall 6, a rounded top 7 and downwardly and rearwardly inclined bottom 8 terminating a distance from the rear wall 6 to provide an opening. A door 9 is hingedly mounted as at 10 on a flange 11 projecting forwardly from the bottom edge of the bottom 8. A manhole 12 is provided in the top

7 and has a disk closure 14 held against the inner end thereof by bolt 15 and upwardly bowed cross member at 16. The front wall 5 has an opening 17 in the top thereof forming the inlet and an opening 18 is formed in the bottom of the rear wall 6 to provide the outlet. A shelf or chute 19 is mounted on the inside of the front wall 5 below the inlet and inclines downwardly and rearwardly. A grate 20 is mounted on the rear wall 6 adjacent the upper end thereof and inclines downwardly and forwardly and is raised by a cross member 21 between the side walls 22 of the box.

The box is supported on suitable frame work 23. Rises 24 on the framework terminate above the box and support bearings 25 in which is journaled a shaft 26 having cranks 27 on the ends thereof. Links 28 are connected with these cranks 27 and extend downwardly and have a pivotal connection as at 30 with an intermediate portion of the door 9. A handle 31 is fixed to an intermediate portion of the shaft 26 and rests on a ledge 32 on the top 7 when the cranks 27 are inclined upwardly and forwardly as is illustrated in full lines in Figure 4. Now by swinging the handle upwardly the cranks may be swung around to a depending position thereby allowing the door to swing down to an open position. A grate is denoted generally by the letter G and is rockably mounted at 33 adjacent the front wall 5 between the side walls 22 and above the upper end of the bottom 8 and normally inclines downwardly and rearwardly and the rear end is supported by arms 34 pivoted to the grate G as at 35 and pivoted on the door 9 as at 36. It will therefore be seen that when the door 9 is swung to an open position the grate G takes the dotted line position shown in Figure 4 allowing stones and the like to roll thereoff through the openings.

This grate G includes a plurality of spaced parallel coextensive bars 38 held in set relationship by bolts 39 with spacers 40 thereon.

The purpose of this invention is to provide a stone box for a sand suction pump, which pumps are used in gravel pits where water is available. The gravel or sand containing

some large stones, larger than is wanted in the pump, comes into the sand box through the inlet and enters the upper portion of the stone box with the grate G in a closed or raised position. The grate is of such a size sufficient to permit only gravel and stones of a desired size to drop through and this gravel drops into the bottom of the box and goes out through the outlet 18. The stones that cannot pass through the grate remain on the upper portion of the stone box and when this becomes filled with stones, by means of the handle 31, the bottom of the stone box is opened and the grate lowered allowing the stones to roll off of the grate out of the box. When the stones have passed through the bottom the door has been closed and the pump is put in operation. The manhole cover in the top is removable so that the operator of the pump can take it off and help push the stones out of the box if this is necessary.

The advantage of this box over those of other stone boxes is that this stone box has a bottom that can be opened by means of the handle 31 and the stones can be taken out through the bottom of the box.

It is thought that the construction, operation and utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

40 It will be apparent that changes in the details of construction, and in the combination and arrangement of parts may be resorted to without departing from the spirit or scope of the invention as hereinafter claimed or sacrificing any of its advantages.

Having thus described my invention what I claim as new is:

1. Means for separating stones from material passing through a suction line comprising a box having an inlet at its front end and an outlet at its rear end located adjacent the bottom of the box, said box having an opening in its bottom adjacent the rear thereof, and said bottom sloping upwardly and forwardly from the opening, a downwardly moving hinged door for closing the opening, means for normally holding the door closed, a grate located in the lower part of the box and pivotally connected at its front end to the front portion of the box, said grate sloping downwardly and rearwardly, a link connecting the rear end of the grate to the door whereby when the door is swung downwardly to open position, the lower end of the grate will project through

the opening, so that stones on the grate will roll down the same and pass through the opening.

2. Means for removing stones from material passing through a suction line comprising a box having an inlet opening in its front wall and an outlet opening in its rear wall, said outlet opening being located adjacent the bottom of the box, said bottom of the box having an opening therein adjacent the rear wall, and said bottom sloping upwardly and forwardly from the opening, a grate located in the lower part of the box and having its front end pivoted to the front part of the box, a link connecting the rear end of the box to the upper face of the door adjacent the rear end of the door whereby the grate will assume an inclined position with its rear end partly projecting thru the opening when the door is swung downwardly, to open position, means for hinging the front end of the door to the bottom of the box, a downwardly and rearwardly inclined baffle connected to the front wall of the box, below the inlet opening, a downwardly and forwardly extending stationary grate connected to the rear wall of the box above the movable grate, means for opening and closing the door and means associated therewith for holding the door in closed position.

3. Means for removing stones from material passing through a suction line comprising a box having an inlet opening in its front wall and an outlet opening in its rear wall, said outlet opening being located adjacent the bottom of the box, said bottom of the box having an opening therein adjacent the rear wall, said bottom sloping upwardly and forwardly from the opening, a grate located in the lower part of the box and having its front end pivoted to the front part of the box, a link connecting the rear end of the box to the upper face of the door adjacent the rear end of the door whereby the grate will assume an inclined position with its rear end partly projecting through the opening when the door is swung downwardly, to open position, means for hinging the front end of the door to the bottom of the box, a downwardly and rearwardly inclined baffle connected to the front wall of the box, below the inlet opening, a downwardly and forwardly extending stationary grate connected to the rear wall of the box above the movable grate, means for opening and closing the door and means associated therewith for holding the door in closed position, and a manhole opening in the top of the box.

In testimony whereof I affix my signature.
CLARENCE A. ROMINE.
